TRIMMING MACHINE

Charles G. Brostrom, Salem, Mass., assignor to
 United Shoe Machinery Corporation, Borough
 of Flemington, N. J., a corporation of New
 Jersey

Application January 17, 1940, Serial No. 314,257

16 Claims. (Cl. 12—82)

This invention relates to trimming machines and is herein illustrated as embodied in a machine designed to trim the inseams of welted shoes. One of the novel features of the invention is embodied in an improved type of rotary cutter-head the cutting effect of which is smooth and desirable for the operation specified above.

Present-day requirements of inseam-trimming are exacting with respect to smoothness, uniformity, and closeness to the inseam stitches. Many shoe manufacturers demand an inseam-trimming machine that will sever the surplus inseamed materials almost but not quite to the stitch-line. Some of them are dissatisfied if these materials project $\frac{1}{2}$ of an inch beyond the outer stitch-line at any point. It is possible, of course, to trim within the range mentioned, but when this is done with inseam-trimming machines of the types heretofore available for this operation, the problem is aggravated by the risk of trimming to or actually into some of the stitches at certain points because the irregularities in the configuration of an inseam require swinging the ends of a shoe laterally, and these motions must be compounded with various rocking motions required to counteract the various surface irregularities of a shoe bottom. These compounded swinging and rocking motions are most troublesome while traversing those portions of an inseam that extend along the hump in the region of the ball-line and the incurves extending therefrom into the shank. The conditions are especially difficult also at the toe-end where the thickness of the inseam is greatest because of the presence of a toe-stiffener and the pleats formed in that region incidentally to toe-lasting.

The type of inseam-trimming machine most commonly used is illustrated and described in United States Letters Patent No. 1,226,872, granted May 22, 1917, on application of A. Eppler. In a machine of that type the trimming cutter is cup-shaped, its axial dimension being about three inches and the diameter of its annular cutting edge being about four and one-half inches. This type of cutter performs a satisfactory trimming operation on shanks intended for low heels, but when used to operate on women's high-arch shoes that require the maximum rocking motion while traversing the shank and the region of the ball-line, the butt-end of the cutter frequently prevents rocking the shoe as much as the conditions require, with the result that the trimming is forced to deviate too far from the intended line and may cut into the stitches unless adjustments are made that keep

the line of trimming too far from the stitch-line at other portions of the shoe.

In view of these conditions, an object of the present invention is to provide an improved type of cutter-head that will not only insure smooth, even trimming but will also avoid obstructing the necessary rocking motions, including those of greatest amplitude, required by women's high-arch shoes.

As herein illustrated, the improved cutter-head is arranged to rotate about a fixed axis, one or more individual circular cutters carried thereby are arranged to travel in an orbital path around the fixed axis and to rotate about individual axes each offset from the axis of the cutter-head and skewed relatively thereto, each of the cutters having a circular peripheral cutting edge. The individual rotatability of the cutters provides for utilizing all the segments of each cutting edge equally, and, although only a short segment of each cutting edge is effective at any one time, the wear and the dulling effect of use are equally distributed along the edge. The skewed relation of the individual cutter axes to the axis of rotation of the cutter-head develops a force that tends to turn each cutter about its individual axis in consequence of encountering the work and this force alone would be sufficient to bring successive portions of the cutting edges into operation automatically, but the invention also provides supplemental power driven means by which the cutters may be rotated about their individual axes to insure uniform distribution of the cutting burden on all portions of the cutting edges. Another reason for providing supplemental means for rotating the cutters about their individual axes is to insure uniformity of sharpening by an abrading wheel that may be brought into operation without interrupting the rotation of the cutter-head. The cutter-head, by reason of its novel features of construction, provides not only an improved cutting action for inseam-trimming but also an improved sharpening operation when the abrading wheel is presented to the cutters.

In the drawings,

Fig. 1 is a front elevation of the head of a machine embodying the improved features and principles of the present invention;

Fig. 2 is a plan view of the machine;

Fig. 3 is a sectional view of the cutter head, the driving means therefor, and the grinder for sharpening the edges of the cutters;

Fig. 4 is a view illustrating the gearing carried by the cutter-head for driving the cutters;

Fig. 5 is a perspective view illustrating the grinder and the supporting means therefor;

Fig. 6 is a perspective view including the fore-part of a welted shoe, the cutter-head, the feed wheel, the presser foot, and the channel guide, the shoe being in the process of being trimmed;

Fig. 7 is a view illustrating one means by which the speed of rotation of the cutters about their own axes may be varied;

Fig. 8 is a plan view illustrating the operating mechanism for reciprocating the presser foot;

Fig. 9 is a side elevation of the mechanism shown in Fig. 8 and including other elements, one of which is the means for operating the feed wheel; and

Fig. 10 is a detail view of a portion of the mechanism for varying the speed of rotation of the cutters about their own axes.

The supporting frame of the machine is represented by the reference character 10 in Fig. 1, this frame being mounted on any suitable base. The frame 10 extends upwardly and rearwardly of the machine and the rearward portion thereof is formed as a bearing 12 (Fig. 2), having a cylindrical bore 14 therethrough. A sleeve or bushing 16 is carried by the bore in the bearing 12 and forms a journal for a drive shaft 18. A cutter-head supporting arm 20 is mounted on extended portions 22 of the sleeve 16 by means of spaced bearings 24 and 26 formed adjacent to the rearward end of the arm 20. The forward end of the arm 20 carries a cutter-head to be presently described and is arranged for vertical adjustment. To adjust the vertical position of the forward end of the arm 20, an adjusting screw 28 is threadedly carried by the arm 20 adjacent to its forward end, this screw being provided with a hand wheel 30 for facilitating adjustment thereof. The lower end of the screw 28 passes through the arm 20 and bears against a portion of the supporting frame 10, this screw 28 thus acting as an adjustable support for maintaining the forward end of the arm 20 at a desired heightwise position with respect to the frame of the machine. In order further to support the forward end of the arm 20, an adjustable brace 32 (Fig. 1) is provided. The lower end of the brace 32 is substantially spherical and is held against the frame of the machine by means of a bracket 34 secured by means of a screw 36 to the frame of the machine. The upper end of the bracket 34 has a socket portion for receiving the lower end of the brace 32 and a similar socket is formed in the vertical wall of the frame 10. The upper end of the brace 32 is similarly formed and is secured by means of a bracket 38 (Fig. 2) to the supporting arm 20. The brace is formed with a telescopic portion 40 (Fig. 1) by means of which the length of the brace may be varied in accordance with the adjusted position of the forward end of the supporting arm and a set screw 42 is provided for preventing contraction of the brace after the arm has been adjusted to its proper vertical position. The spherical ends of the brace permit relative movement of the brace with respect to the frame and arm as the arm is rocked about the sleeve 16.

The forward end of the arm 20 has secured thereto by means of the screws 44 a cutter-head supporting block 46. This block is formed with a dovetail groove 48 (Fig. 1) for slidably receiving the cutter-head supporting bracket 50. An adjusting screw 52 (Figs. 1 and 3) is threaded into the right end of the bracket 50 and is maintained against lengthwise movement with respect to the supporting block 46 by means of an arm

54 secured to the right end of the block and having a recess 56 through which the screw passes. The screw has a head 58 engaging one side of the plate 54, and a collar 60 fixedly secured to the screw engages the other side of the plate. Rotation of the screw 52 by means of the head 58 will cause lengthwise adjustment of the bracket 50 with respect to the supporting block 46. Indicia 62 (Fig. 1) may be provided on the front of 10 the block and the bracket to indicate the degree of adjustment.

The bracket 50 (Fig. 3) has a pair of depending arms 62 and 64 having aligned apertures in which are received ball bearings 66 and 68 respectively. 15 Supported by these ball bearings is a cylindrical extension 70 of a cutter head 72, this extension 70 passing outwardly beyond the ball bearing 68 and being threaded to receive a nut 74. The left end of the extension 70 adjacent to the head 72 is enlarged at 76 and this enlarged portion is maintained against the inner race of the ball bearing 66 by means of the nut 74. A sleeve 78 surrounds the cylindrical extension 70 of the cutter-head 72 between the bearings 66 and 68 and forms a spacer member for preventing movement 20 of the bearing 68 toward the bearing 66 upon tightening of the nut 74. A pulley 80 is mounted on the sleeve 78 and is fixed to the cylindrical extension 70 by means of a set screw 82. A washer 84 is provided between the bearing 66 and the cutter head 72 to prevent the entrance of foreign material from the cutter-head into the bearing. 25

Rotatably mounted in the cylindrical extension 70 and the cutter-head 72 and concentric with the extension 70 is a drive shaft 86 carrying at its extreme right end a drive pulley 88 secured thereto by means of a set screw 90. The shaft 86 is somewhat smaller than the bore through the extension 70 and a bushing 92 is fitted into the 30 right end of the extension 76 to form a bearing surface for the right end of the shaft 86. The opposite end of the shaft 86 is journaled in the head 72 so that the shaft 86 may be rotated with respect to the head if the pulleys 80 and 88 are 35 rotated at different speeds.

The cutter-head 72 is generally square in cross section with the outer edges thereof beveled off to form bearing surfaces for the inner sides of cutters 96 and 98. The head 72 has a cylindrical bore 100 extending therethrough for housing 40 gearing for transmitting motion from the shaft 86 to the cutters. The shaft 86 carries a skew gear 102 (Fig. 4), this gear being located in the vertical passageway in the head 72. The gear 102 engages skew gears 104 and 106 located on opposite sides of the gear 102 in the aperture 100 of the head 72. The axes of the gears 104 and 106 are arranged at right angles to each other and are skewed with respect to the drive shaft 86. The skew gears 104 and 106 are pinned to shafts 108 and 110 respectively, these shafts being journaled in the head 72 by means of bushings 112 (Fig. 3). The shafts 108 and 110 are threaded at their outer ends for receiving nuts 114 having frusto-conical exterior surfaces 45 for engaging similarly shaped openings in the cutters to maintain these cutters against collars 116 formed adjacent to the outer ends of the shafts. The opposite ends of the shafts are squared as at 118 for receiving a wrench to prevent rotation of the shafts while the nuts 114 are being tightened. In assembling the shafts and gears in the head 72, the bushings for supporting the shafts are first inserted by means 50 of the aperture through the central part of the

head. A gear is then held in alignment with the bushings and the appropriate shaft is then inserted through the gear and the bushings. A pin 120 is then inserted through a collar 121 integral with the gear and through the shaft to prevent relative movement between the shaft and gear. Each gear has reduced collar portions at each side thereof, as indicated in Fig. 4, these collar portions engaging the ends of the bushings 112 to prevent axial movement of the gear and consequently of the cutter supporting shaft which is pinned thereto. It should now be understood that rotation of the shaft 86 relative to the cutter-head 72 will cause rotation of the cutters 96 and 98 about their own axes, the speed of rotation depending upon the difference in the relative speeds between the shaft and the cutter-head. If the cutter-head is rotated at a speed which is the same as the speed of the shaft 86, and in the same direction, there will be no relative movement between the drive gear 102 in the cutter-head and the gears 104 and 106 and consequently there will be no rotation of the cutters about their own axes.

The shaft 18 (Fig. 2) carries a driving pulley 120 which is connected to the pulley 80 by means of the belt 122. The shaft 18 carries a second pulley 124 connected to the pulley 88 by means of a belt 126. The diameter of the pulley 124 is somewhat less than the diameter of the pulley 120, whereas the pulleys 80 and 88 are of the same diameters. If there is no substantial slippage between the belts and the respective pulleys, the speed of rotation of the driven pulley 88 will be somewhat less than that of the driven pulley 80. If, however, the belt 126 connecting the pulleys 88 and 124 be removed or be loosened to such an extent that it does not transmit any motion from the pulley 124 to the pulley 128, the shaft 86 will tend to rotate at the same speed as the cutter head 72 because of the drag thereon imposed by the skew gears in the cutter-head. Thus, if the belt 126 is sufficiently loose, there will be no relative movement between the shaft 86 and the cutter-head and, accordingly, there will be no movement of the cutters about their own axes unless some external force acts upon the cutters and exerts a drag upon them during the rotation of the head 72, which may occur whenever the cutters are engaging work to be trimmed. If the belt 126 is gradually tightened from the loose condition which has just been presumed to exist, the speed of rotation of the shaft 86 will gradually decrease to a speed corresponding to the diameter of the pulley 124 and, accordingly, as the tension on the belt is increased, the speed of the shaft 86 will be gradually reduced, thus increasing the relative speed between the shaft and the cutter-head 72 which, in turn, causes an increase in the speed of rotation of the cutters about their own axes.

The means for adjusting the tension on the belt 126 is illustrated in Figs. 2, 7 and 10. An idler pulley 130 carried by an arm 132 engages the belt 126 and is prevented from accidental removal from the belt by means of the guards 134 on each side of the pulley. The arm 132 is pinned to a shaft 134 extending transversely of the machine at the rear thereof. The shaft 134 is journaled in bearings 136 and 138 carried by an arm 140 extending transversely of the machine below the shaft 134. The arm 140 is connected to the cutter-head supporting arm 20 by means of the arms 142 and 144 which are formed as

extensions of the bearings 24 and 26 respectively. A third arm 146 supports the end of the arm 140 adjacent to the pulley 124, the forward end of the arm 146 being journaled to the shaft 18 as indicated in Fig. 7. An arm 150 is pinned to the shaft 134 and the other end of this arm is pivoted to a member 154 (Fig. 10) which embraces a reduced portion of a screw 156 threaded into a boss 157 extending laterally from the arm 144. A hand wheel 158 is connected to the upper end of the screw 156 for facilitating the turning of the screw and for adjusting the position of the arm 150 which, in turn, adjusts the shaft 134. As the shaft 134 is turned, the vertical position of the idler pulley 130 is varied to adjust the tension on the belt 126. In this manner, the speed of rotation of the cutters about their own axes may be readily varied.

In order to feed the work past the cutters, the feed wheel 162 (Figs. 1, 6, 8, and 9) is provided. This feed wheel is frusto-conical in shape and the upper surface thereof is concave or dished in order to permit passage of the cutters thereover. The edge of the feed wheel is sharp and forms a shearing edge and the cutters approach this edge at an angle to the radius of the wheel so as to give a shearing cut to the work. The under surface of the feed wheel is roughened or ribbed as indicated in Fig. 6 so as to grip the welt of the shoe which is pressed thereagainst by means of a presser foot 164 which enters the crease between the welt and the upper (Fig. 9).

The feed wheel 162 is mounted on a shaft 166 mounted in an arm 168 rigid with the frame 10 of the machine and extending upwardly and forwardly thereof. This shaft is mounted at an angle to the vertical so that the feed wheel will feed the work in a substantially horizontal plane. The lower end of the shaft 166 carries a bevel gear 170 which engages a second bevel gear 172 mounted on a shaft 174 extending toward the rear of the machine (Fig. 9). The rear end of the shaft 174 carries a sprocket wheel 176 over which passes a sprocket chain 178 connected to a suitable driving means. The feed wheel is rotated slowly to move the work slowly past the cutters which are being revolved about the axis of the cutter-head 72 at a relatively high speed to impart a shearing cut to the inseam I which is upstanding, as shown in Fig. 9.

A pressure arm 180 engages the lower side of the presser foot 164 to urge the presser foot against the welt with a predetermined pressure. In order to reduce the frictional drag between the presser foot 164 and the welt, the presser foot is arranged to be reciprocated rapidly during the feeding movement of the work. The presser foot reciprocates relatively to the pressure arm 180 and in order to reduce friction between these two parts a small steel ball 185 (Figs. 1 and 6) is mounted in the end of the pressure arm and forms the contact surface between the arm and the presser foot 164. The rearward end of the presser foot 164 is secured to an arm 181 which is, in turn, pivoted to a stub shaft 182 by means of spaced bearing members 183 for movement in a vertical plane. The stub shaft 182 is fixedly secured in the forward end of an arm 184 lying between the bearing members 183 by means of a set screw 186 and the arm 184 is mounted on a shaft 190 for movement in a horizontal plane. The shaft 190 is rotatably mounted in a bearing 192 fixed to the side of the arm 168 and a collar 194 is fixed to the shaft 190 below the bearing 192 to prevent endwise move-

ment of the shaft. An L-shaped arm 186 is fixed by means of a set screw 198 to the rearward end of the arm 184 and the other end of the L-shaped arm 186 carries a cam follower 200 which rides in the peripheral cam groove of a cam 202 fixed to the left end of the shaft 18. Accordingly, as the shaft 18 rotates to drive the cutter-head and the cutters, the presser foot 164 will be reciprocated by means of the cam 200 about the axis of the shaft 190 so as to reduce the frictional drag between the presser foot 164 and the welt W of the shoe, the inseam of which is being trimmed.

The pressure arm 180 which maintains the presser foot 164 against the welt of the shoe is mounted for horizontal adjustment on a slide 206 by means of screws 208, the slide being provided with slots 210 (Fig. 9) to permit horizontal adjustment of the arm 180 with respect thereto. The slide 206 is provided with vertically extending dovetailed grooves which fit over dovetailed slides 210 (Fig. 1) mounted on the frame of the machine. A tension spring 212 is connected by means of a pin 214 to the lower end of the slide 206 and the upper end of this spring is connected by means of a screw 216 to the frame of the machine. The spring, accordingly, urges the slide upwardly so that the arm 180 exerts an upward force on the presser foot 164 to press the welt of the shoe against the feed wheel. An adjustable stop is provided by a screw 228 (Fig. 1) for limiting the upward movement of the slide 206. This screw is threaded through a tapped lug 222 on the frame of the machine and the screw is provided with a lock nut to hold it in adjusted position. The slide 206 is provided with an apertured boss 224 at its lower end for receiving the angular extension of a treadle rod 226, the lower end of which is connected to a treadle (not shown) whereby the slide 206 may be moved downwardly by the operator against the force of the spring 212. A second tension spring 230 is connected at its lower end to the left side of the slide 206 by means of a screw 232 and the upper end of this spring is connected by means of a screw 234 to the presser foot 164. This spring maintains the presser foot in engagement with the ball 185 carried by the arm 180 so that as the arm 180 is moved downwardly by the operator, the presser foot 164 will follow the downward movement and will move away from the lower surface of the feed wheel 162 to facilitate the insertion of a welt between the feed wheel and the presser foot.

In order to maintain the inseam against the edge of the feed wheel 162 a channel guide 240 (Fig. 6) is provided, this guide having a lower end arranged to enter the channel formed by the upstanding rib on the bottom of the insole. The channel guide is connected for vertical adjustment on the lower end of an arm 242 by means of a screw 244 (Figs. 1 and 2), the arm 242 having a vertically extending slot 246 to permit of this adjustment. The arm 242 extends upwardly and rearwardly of the machine, and at its upper end is secured to a shaft 248 by means of set screws 250. The shaft 248 is journaled in brackets 252 which embrace the arm 242, these brackets being integral with a cover plate 254 that extends partially around the cutter head 72 and forms an extension of the cutter-head supporting bracket 50 as indicated in Fig. 3. A spring 260 (Figs. 1 and 2) is connected at its upper end to the channel guide carrying arm 242 by means of a screw 262. The

lower end of this spring is connected to the cover plate 254 by means of a screw 264 and this spring acts to urge the channel guide downwardly and toward the feed wheel 162 to maintain the inseam of the shoe against the periphery of the feed wheel.

In order to facilitate placing of the work in position to be trimmed, it is desirable to move the channel guide outwardly away from the feed wheel when the presser foot 164 is moved downwardly therefrom. For this purpose, a connection is provided between the slide 206 carrying the presser arm 180 and a rearward extension 270 of the arm 242. The rear part of the extension 270 carries a hook member 272, the upper end of which passes through the extension 270 and is threaded to receive a nut 274. A connection such as a chain 276 connects the hook 272 with the slide 206, the slide being provided with a plate 280 which is apertured at its upper end to receive the lower end of the chain as shown in Fig. 1. The chain 276 passes downwardly and rearwardly of the cover member 254 which partially surrounds the cutter-head 72. As the slide 206 is moved downwardly by the operator, the chain 276 will also be moved downwardly and will rock the arm 242 carrying the channel guide in a counterclockwise direction, as viewed in Fig. 1, to move the channel guide upwardly away from the feed wheel 162. After the welt of the shoe, the inseam of which is to be trimmed, is placed between the feed wheel and the presser foot 164, the treadle is released by the operator whereupon the spring 212 moves the slide 206 upwardly and causes the arm 180 carried thereby to move the presser foot 164 upwardly to maintain the welt of the shoe in firm engagement with the lower surface of the feed wheel. At the same time, the spring 260 rocks the arm 242 back to the position illustrated in Fig. 1, whereupon the channel guide enters the channel, forcing the inseam of the shoe against the periphery of the feed wheel 162 and maintaining it in this position during the trimming operation. An adjustable screw 278 threaded through the arm 242 and engaging the cover plate member 254, limits the movement of the channel guide 240 toward the feed wheel 162.

A cover 280 completes the protective casing around the cutter-head, this cover being pivoted at 282 to a laterally extending end of the cover plate 254 (Fig. 2). A screw 284 passes through the forward end of the cover 280 and into the cover plate 254 to lock the cover in closed position. A grinder is rotatably carried by this cover and is adjustably mounted thereon for movement toward and away from the cutters 96 and 98 and enables sharpening of these cutters when necessary without stopping the machine or removing the cutters from the cutter-head.

The cover 280 has a circular opening therethrough and adjacent to one side of the circular opening the cover is provided with a pair of spaced lugs 285, the adjacent sides of which are slotted as at 287 in Fig. 5 to form between them a dovetailed groove. Slidably supported by the lugs 285 is a support 288 for a grinder 286. The support 288 carries a shaft 290 at its rearward end, the shaft being fixedly mounted in the support 286 by means of a set screw 292. Inwardly of the support 288 the shaft 290 is reduced as at 294 (Fig. 3) and a ball bearing 296 is mounted on the shaft against the shoulder formed between the enlarged and reduced portions of the shaft. A pulley 300 is mounted on the ball bear-

ing 296 and integral with this pulley and inwardly of the machine is a flange portion 302 against which the grinder 288 is held by means of a screw 304. The inner surface of the pulley adjacent to the flange portion is threaded for the reception of the screw 304 and this screw is hollow and surrounds the shaft 294. The inner end of the shaft 294 is further reduced and a ball bearing 306 is mounted on this inner portion of the shaft and supports the screw 304 adjacent to the head thereof. A nut 308 is threaded on the inner portion of the shaft 294 and maintains the bearing 306 against a shoulder 310. A belt 312 connects the pulley 300 with a pulley 314 on the drive shaft 18.

The grinder is arranged to grind both of the cutters 97 and 98 during the rotation of the cutter head 72, as indicated in Fig. 3, and the grinder may be adjusted toward or away from the cutters to obtain the proper grinding action and moved away from the cutters after they have been properly sharpened. A screw 316 is threaded through a wall 318 extending laterally from the cover 280. The screw is provided with a pair of collars 322 rigid therewith, these collars engaging opposite sides of the support 286, which support is recessed and reduced at this point as shown in Fig. 5. Rotation of the screw 316 causes movement of the support 286 toward or away from the cutters 97 and 98 and, therefore, the grinder is readily adjusted with respect to the cutters.

The driving shaft 18 is provided with a pulley 326 (Fig. 2) which is connected to any suitable driving means by a belt 328 for causing rotation of the shaft 18.

The coverplate 254 has a substantially cylindrical open extension 330 at the rear part thereof to permit escape of material trimmed from the inseam of the shoe. A conduit 332 is mounted on the frame of the machine and cooperates with the cylindrical extension 330 of the cover plate for conducting the trimmed material to a suitable point of disposal, the conduit 332 being connected, if desired, to a source of suction. In order that the mouth of the conduit 332 register properly with the cylindrical extension 330, it being understood that this extension moves with the cutter-head assembly during adjustment thereof, the conduit 332 is mounted for vertical and horizontal adjustments. The conduit 332 is mounted on a slide 334 (Fig. 1) which is, in turn, mounted for horizontal adjustment on a support 336. A screw 338 holds the support 336 in the desired horizontal position. The support 336 is bolted to the frame of the machine by means of a screw 340 and the support 336 has a vertical slot 342 for permitting vertical adjustment of the support relative to the frame of the machine.

In the use of the machine, the cutter-head support 46 will be adjusted vertically by means of the hand wheel 30 and the position of the cutter-head laterally and vertically of the feed wheel may be adjusted by means of the screw 52. When the cutter-head is properly adjusted, the cutter will pass over the forward edge of the feed wheel very close thereto so as to trim the material with a shearing cut. The tension of the belt 126 may be adjusted by means of the hand wheel 158 (Fig. 2) to provide the desired speed of the shaft 86 relative to the speed of rotation of the cutter-head 72 so that the cutters will rotate about their individual axes at the desired rate of speed. By reason of this rotation of the cutters about their

individual axes, a different surface of each cutter will be presented to the material being trimmed at each rotation of the cutter-head, thus prolonging the cutting surfaces of the cutters so that infrequent sharpening thereof will be required.

After the machine has been properly adjusted, and it is obvious that such adjustments will be made at infrequent intervals only, the machine 10 is ready for use. In presenting the work to the machine, the operator steps on the treadle which moves the slide 206 downwardly against the force of the spring 212 and this downward movement of the slide causes a similar movement of the presser foot 164 so that the presser foot may be inserted in the crease between the welt and the upper. At the same time, the channel guide moves upwardly and away from the feed wheel 162, thus facilitating the positioning of the shoe 20 in the machine. After the shoe is properly positioned, the treadle is released and the presser foot presses the welt against the lower roughened surface of the feed wheel 162. At the same time, the channel guide enters the channel formed during the formation of the rib and urges the rib and the inseam materials toward the feed wheel so that the shoe is maintained in proper position with respect thereto. The work is fed by the feed wheel during which time the cutter-head rotates rapidly so that the inseam is trimmed throughout the entire extent of the welt. The cutters offer no obstruction to any rocking motion of the shoe that may be required such as when traversing those portions of the inseam 35 that extend along the hump in the region of the ball-line and the incurves extending therefrom into the shank, so that the cutters may cut the inseam close to the line of stitching at all points. The cutters perform a shearing cut in the inseam 40 due to the fact that the cutters approach the feed wheel at an angle to the radius thereof and, accordingly, the inseam is trimmed with a smooth cut throughout the extent thereof. While two cutters have been illustrated as being carried by the cutter head 72 it is to be understood that the machine would operate satisfactorily with only a single cutter or, if desired, more than two cutters could be employed. While the cutters in the illustrated machine are positively rotated about their own axes, this positive drive might be dispensed with since the cutters approach the feed wheel at such an angle that a turning force is imparted thereto upon contact with the work being trimmed.

Having thus described my invention, what I claim as new and desire to secure by Letters Patent of the United States is:

1. In a trimming machine, a cutting disk having a circular cutting edge, a carrier by which said disk is moved in an endless path, means for driving said carrier, a work engaging member having a shearing edge transverse to said path and across which said cutting disk is moved by said carrier in shearing relation thereto, and means for rotating said cutting disk about an axis concentric with its cutting edge.

2. In a trimming machine, a cutter head, means for rotating said cutter head about an axis, a cutting disk having a circular cutting edge, said disk being carried bodily by said cutter head in an orbital path about said axis, means for rotating said cutting disk about an individual axis concentric with its cutting edge, and a work-engaging member having a shearing edge transverse to said orbital path and across which

said cutting disk is moved by said cutter head in shearing relation thereto.

3. In a trimming machine, a cutter head rotatable about an axis, a cutting disk carried bodily by said cutter head in an orbital path, said disk being rotatable about an individual axis in skewed relation to the first axis and having a circular cutting edge concentric with said individual axis, a work-engaging member having a shearing edge transverse to said orbital path and across which said cutter is moved by said cutter head in shearing relation thereto, means for rotating said cutter head, and means for simultaneously rotating said cutting disk about its individual axis.

4. In a trimming machine, a rotatable cutter head, means for driving said cutter head, a cutting disk having a circular cutting edge, said disk being carried by said cutter head for bodily movement in an orbital path about the axis of rotation of said cutter head, a work-engaging member having a shearing edge transverse to said path and across which said cutter is moved by said cutter head in shearing relation thereto, means for rotating said cutting disk about an axis offset from said cutter head, and means for holding a work piece against said work-engaging member with the portion to be trimmed against said shearing edge.

5. In a trimming machine, a series of individual rotatable cutters each having a peripheral cutting edge concentric to its axis of rotation, a member for bracing work to be trimmed against the action of said cutters, said member having a sharp edge, means for bodily moving said cutters one after another in shearing relation to said sharp edge, and means for simultaneously rotating said cutters about their individual axes.

6. In a trimming machine, a rotatable cutter head, a cutting disk carried bodily by said cutter head in an orbital path about the axis of rotation of said cutter head and for individual rotation about its own axis, means for rotating said cutter head about its axis of rotation and for simultaneously rotating said cutting disk about its axis, and a feed wheel having a circular peripheral work-engaging edge the work-engaging segment of which is transverse to the path of movement of said cutting disk and across which said cutting disk is moved in shearing relation.

7. In a trimming machine, a feed wheel having a sharp peripheral edge, a rotatable cutter having a circular peripheral cutting edge concentric to the axis thereof, means for holding a work piece against said feed wheel with the portion of the work piece which is to be trimmed against said edge, means for continuously moving said cutter bodily in a closed path in which it moves rapidly past said feed wheel in shearing relation to the edge thereof, and means for simultaneously rotating said cutter about its own axis.

8. An inseam trimmer comprising a circular feed wheel having a sharp peripheral edge, means for rotating said feed wheel, a rotatable cutter having a circular peripheral cutting edge concentric to the axis thereof, a presser finger for holding the welt of a shoe against said feed wheel with the inseam portion to be trimmed against said peripheral cutting edge, means for reciprocating said presser finger in the line of feeding movement, means for bodily moving said cutter past said feed wheel in shearing relation to the edge thereof, and means for simultaneously rotating said cutter about its own axis.

9. In a machine for operating on shoe parts, 75

means for feeding a work piece, said means comprising a rotatable feed wheel having a roughened surface for engaging the work piece to be fed, a presser finger for maintaining the work piece to be fed continuously against the roughened surface of said feed wheel, means for continuously rotating said feed wheel, and means for rapidly reciprocating said presser finger in the line of movement of the work piece.

10. In a trimming machine, a cutter-head having an axis of rotation and power-driven means for operating it, a trimming cutter carried by said cutter-head and having an individual axis of rotation movable around the axis first mentioned, an abrading member arranged to generate an acute cutting edge on said cutter in consequence of rotating said cutter-head about its said axis, a work-engaging member having an edge in shearing relation to said cutter, and power-driven means arranged to rotate said cutter about its individual axis while the cutter-head is in rotation to present different segments of the cutter in successive revolutions of the cutter-head to the work or to said abrading member or to both, as the case may be.

11. In a trimming machine, a rotatably mounted cutter-head, a cutter carried thereby for rotation about an axis offset from the axis of said cutter-head and skewed relatively thereto, said cutter having a circular peripheral edge concentric to said offset axis, means for rotating said cutter-head to cause said cutter to travel in a circular path concentric to the axis of said cutter-head, and means synchronized with said last named means for simultaneously rotating said cutter about its own axis at a relatively slow speed compared to the speed of rotation of said cutter-head.

12. In a trimming machine, a rotatably mounted cutter-head, a cutter carried thereby for rotation about an axis offset relative to the axis of said cutter-head and skewed relatively thereto, said cutter having a circular peripheral edge concentric to said offset axis, a circular work feeding member arranged to brace work to be trimmed against the action of said cutter and having a sharp edge in shearing relation to the peripheral edge of said cutter, means for rotating said cutter-head relative to said work feeding member to cause said cutter to travel in a circular path concentric to the axis of said cutter-head and to move past the feeding member in shearing relation thereto, and means for rotating said work feeding member to feed the work past said cutter.

13. In a trimming machine, a rotatably mounted cutter-head, a pair of cutters carried thereby for rotation about axes on opposite sides of the axis of said cutter-head and skewed relatively and oppositely thereto, said axes being so disposed that said cutters will follow one another in a circular path concentric to the axis of said cutter-head upon rotation of said cutter-head, means for rotating said cutter-head, and means for rotating said cutters at equal speeds and at a speed slower than the speed of rotation of said cutter-head during their movement in a circular path by said cutter-head.

14. In a trimming machine, a rotatably mounted cutter-head, a cutter carried thereby for rotation about an axis offset relative to the axis of said cutter-head and skewed relatively thereto, said cutter having a circular peripheral edge concentric to said offset axis, a transmission shaft in said head and rotatable with respect thereto

about the axis of said head and connected to said cutter, means for rotating said cutter-head to cause said cutter to travel in a circular path concentric to the axis of said cutter-head, and means for simultaneously rotating said transmission shaft at a speed somewhat slower than the speed of rotation of said cutter-head to cause said cutter to rotate slowly about its own axis.

15. In a trimming machine, a rotatably mounted cutter-head, a pair of cutters carried thereby for rotation about axes disposed on opposite sides of the axis of rotation of said cutter-head, a transmission shaft carried by said cutter-head between the axes of said cutters, said shaft being rotatable with respect to said cutter head and operatively connected to said cutters, means for rotating said cutter-head to cause said cutters to follow one another in a circular path concentric to the axis of said cutter-head, and means for rotating said transmission shaft at a speed somewhat less than the speed of rotation of said cutter-head to cause rotation of said cutters about their own axes at a slow speed.

16. In a trimming machine, a rotatably mounted cutter-head, a pair of cutters carried thereby for rotation about axes disposed on opposite sides of the axis of rotation of said cutter-head, a transmission shaft carried by said cutter-head between the axes of said cutters, said shaft being rotatable with respect to said cutter-head and operatively connected to said cutters, means for rotating said cutter-head to cause said cutters to follow one another in a circular path concentric to the axis of said cutter-head, means for rotating said transmission shaft at a speed somewhat less than the speed of rotation of said cutter-head to cause rotation of said cutters about their own axes at a slow speed, and means for adjusting the speed of rotation of said transmission shaft to vary the speed of rotation of said cutters about their own axes without affecting the speed of rotation of said cutter-head.
